US0D1073624S

(12) **United States Design Patent** (10) **Patent No.:** **US D1,073,624 S**
(45) **Date of Patent:** **** May 6, 2025**

(54) **CONNECTOR**

(71) Applicant: **LS Mtron Ltd.**, Anyang-si (KR)

(72) Inventor: **Dong Wan Kim**, Anyang-si (KR)

(73) Assignee: **LS MTRON LTD.**, Anyang-si (KR)

(**) Term: **15 Years**

(21) Appl. No.: **29/886,038**

(22) Filed: **Mar. 3, 2023**

(30) **Foreign Application Priority Data**

Sep. 8, 2022 (KR) 30-2022-0036925

(51) **LOC (15) Cl.** **13-03**

(52) **U.S. Cl.**

USPC **D13/147**

(57) **CLAIM**

The ornamental design for a connector as shown and described.

DESCRIPTION

FIG. 1 is a perspective view of a connector showing the new design;
FIG. 2 is a front view thereof;

FIG. 3 is a rear view thereof based on FIG. 2;

FIG. 4 is a left-side view thereof based on FIG. 2;

FIG. 5 is a right-side view thereof based on FIG. 2;

FIG. 6 is a top plan view thereof based on FIG. 2;

FIG. 7 is a bottom view thereof based on FIG. 2; and,

FIG. 8 is a bottom perspective view thereof based on FIG. 2.

1 Claim, 8 Drawing Sheets
